UNITED STATES PATENT OFFICE.

CHARLES E. WALDECK, OF PHILADELPHIA, PENNSYLVANIA.

HANDLE.

SPECIFICATION forming part of Letters Patent No. 241,098, dated May 3, 1881.

Application filed December 20, 1880. (No model.)

To all whom it may concern:

Be it known that I, CHARLES E. WALDECK, a subject of the Emperor of Germany, residing in Philadelphia, Pennsylvania, United States 5 of America, have invented an Improvement in the Manufacture of Pearl Handles, &c., of which the following is a specification.

My invention relates to an improvement in that class of handles which are ornamented 10 with strips of pearl-shell, the object of my invention being to make in a simple manner a strong and permanent handle of this class.

In the accompanying drawings, Figure 1 is 15 a view, drawn to an enlarged scale and partly in section, showing the pieces of which the handle is composed, said pieces being detached from each other; Fig. 2, a side view of part of Fig. 1; Fig. 3, a section on the line 1 2 of part of the handle; Fig. 4, an exterior view of the 20 handle drawn to a reduced scale; Fig. 5, a view of a modified form of handle, also drawn to a reduced scale; Fig. 6, another form of handle drawn to an enlarged scale, and partly in section; and Fig. 7, a perspective view of 25 a section of one of the tubes composing the handle.

In Figs. 1, 2, 3, and 4, A represents the stem 30 of the handle, secured to a door or drawer, B, the outer portion of this stem consisting of a ring, a.

Strips b, of pearl, reduced to wedge shape, as 35 shown in Fig. 7, are fitted and temporarily secured together, and are then turned in a lathe so as to form a tube, E, which in the present instance is of a tapering form, and which is reduced at the opposite ends, e and f. Two of these tubes will in most cases be required in making a handle, the reduced ends e of the tubes being fitted into the ring a of the stem, 40 and a cap, F, being fitted to the reduced end f of each tube, a central rod, G, serving to secure the whole firmly together. This rod may be threaded at each end and adapted to internally-threaded openings in the caps F; or the 45 rod may be riveted at each end, or may have ornamental nuts bearing against the caps; or it may have a head at one end and a nut on

the other end. Indeed, it is immaterial how the rod is constructed, providing it serves to confine the caps and tubes to the ring of the stem 50 A, the completed handle presenting the appearance shown in Fig. 4, and the pearl portion having the highly-attractive iridescent appearance peculiar to pearl-shell. Each tube E has, in the present instance, a tubular core, 55 x, of wood or cork; but this is not essential in carrying out my invention, nor is it necessary to reduce the tapering tubes of pearl-shell at the ends, as the small ends of the tubes may fit against a shoulder in the ring a, as shown 60 by dotted lines in Fig. 1, and the caps F may overlap the tubes.

My improved handles may be used for carriage-doors or safe-doors, in which cases they will be combined with latching or locking 65 mechanism.

My invention may also be applied to handles of the character shown in Fig. 5, in which case one tube only of pearl-shell will be required; or the invention may be adopted in the manufacture of pendulous handles, as shown in Fig. 6, in which the ring a for receiving the ends of the pearl-shell tubes forms part of an arm, H, which is pivoted to a bracket, I, secured to the 70 front of a door or other object.

Handles for umbrellas, parasols, &c., may consist of a central ring, opposite end caps, tubes, and a connecting-rod; or a single tube and connecting-rod may be combined with two end caps, the central ring being dispensed with. 75

I claim as my invention—

A handle in which a ring, a, forming part of the stem or arm of the handle, is combined with a tube or tubes composed of strips of pearl-shell, a cap or caps, F, and a connecting- 80 rod, G, all substantially as described.

In testimony whereof I have signed my name to this specification in the presence of two subscribing witnesses.

CH. E. WALDECK.
